UNITED STATES PATENT OFFICE.

LOREN P. MICHAEL, OF ELMHURST, ILLINOIS, ASSIGNOR OF ONE-HALF TO HARRY T. BENTLEY, OF OAK PARK, ILLINOIS.

BOILER.

Application filed February 23, 1923. Serial No. 620,557.

To all whom it may concern:

Be it known that I, LOREN P. MICHAEL, a citizen of the United States, residing at Elmhurst, in the county of Du Page and State of Illinois, have invented certain new and useful Improvements in Boilers, of which the following is a specification.

This invention relates to improvements in boilers, and has reference more particularly to boilers of the water tube type. The invention has been designed more especially with reference to its adaptation to, and use as, a locomotive boiler; but its novel structural principles are also equally adaptable to water tube boilers of the marine and stationary types; and although I have herein shown and described a particular embodiment of the invention adaptable to locomotive practice, it should be understood that, in its broad aspects, the invention is by no means limited to locomotive boilers but also comprehends boilers of all other kinds and for all other purposes wherein steam is generated from water circulating through tubes bathed in products of combustion from the fire box and also subject to the radiant heat of the fire.

Among the salient objects of the invention are, to provide an improved water tube boiler of very compact construction and relatively light weight, especially as compared with the standard locomotive type construction; to provide an improved water tube boiler that will have a much higher efficiency and will evaporate a much larger quantity of water per square foot of heating surface than the present locomotive or fire box type of boiler; to provide an improved water tube boiler of such a construction that it will have a comparatively small external radiating surface, and will effect a very rapid circulation of the entire volume of water in the boiler when in service. Other objects are to provide a construction readily permitting of repairs and renewal of parts, and especially the removal and replacement of the water tubes without the necessity of removing other tubes than those required to be removed and replaced; to provide an improved construction permitting the use of the maximum number of water tubes within the space limits of the boiler; to provide a construction of water tube boiler wherein the arrangement of tubes shall be such as to afford a strong, well braced, and rigid

construction; and to provide a construction of water tube boiler well adapted to the application of superheating apparatus.

Other objects and attendant advantages of the invention will be apparent to persons skilled in the art as the same becomes better understood by reference to the following detailed description, taken in connection with the accompanying drawings, wherein I have illustrated one practical and approved mechanical form of the invention as embodied in a boiler more especially designed for locomotive practice, and in which—

Fig. 1 is a vertical longitudinal section of my improved boiler taken on the line 1—1 of Fig. 2;

Fig. 2 is a vertical cross section taken on the line 2—2 of Fig. 1;

Fig. 3 is a vertical cross section taken on the line 3—3 of Fig. 1 just inside the front wall of the boiler casing and showing the arrangement of tubes at the front end of the boiler;

Fig. 4 is a horizontal section on the line 4—4 of Fig. 3;

Fig. 5 is a vertical section taken on the line 5—5 of Fig. 1 and showing in elevation the arrangement of tubes at the rear end of the boiler; and

Fig. 6 is a horizontal section on the line 6—6 of Fig. 5.

Referring to the drawings 5 designates the side walls, 6 the top wall, 7 the front wall and 8 the rear wall of a generally rectangular boiler shell or housing; these walls being provided with internal linings of suitable fire resisting insulating material such as sheets or plates of asbestos designated by 5', 6', 7' and 8', respectively.

Located within and extending lengthwise of the corner regions of the boiler housing are four circular drums. The two lower drums, designated by 9 and 9', may be mounted in cradles 10, 10', or other suitable supports, on and between the inner edges of which extends a coal-burning grate conventionally shown at 11. 12 and 12' designate the corresponding steam and water drums mounted in the upper corner regions of the housing.

Inner baffle walls or plates 13, 13' of high temperature cement or other suitable material extend from the lower drums 9, 9', upwardly substantially parallel with the sides

- of the boiler housing, curving thence inwardly toward each other and terminating preferably at or slightly above the horizontal plane of the axes of the upper drums 12, 12', as clearly shown in Fig. 2. Outer baffle walls or plates 14, 14' extend downwardly from the drums 12, 12', terminating a slight distance above the lower drums 9, 9'.
 Connecting the lower and upper drums 9 and 12, and disposed between the adjacent side wall of the boiler housing and the baffle 14 are a plurality of rows, herein shown as three, of tubes 15, extending the full length of the boiler; these tubes constituting down-flow tubes for water not evaporated in the steam and water drum 12 from the latter to the water drum 9. An identical series of tubes 15' connects the drums 9' and 12' on the opposite side of the boiler.
 10 Inwardly of the baffles 14, a plurality of longitudinal rows, herein shown as four, of tubes 16 extend from the drum 9 upwardly and thence obliquely across the upper portion of the boiler above the fire-box into the steam and water drum 12' on the other side; the tubes of three of the rows being shown as starting from points in the drum 9 behind the baffle 13, and extending through the latter and the opposite baffle 13', and the tubes 20 of the innermost row being shown as starting from points in front of the baffle 13 and extending through the companion baffle 13'. Similar and oppositely inclined rows of tubes 16' connect the lower water drum 9' with the upper steam and water drum 12. To permit the upper inclined portions of the two series of tubes 16 and 16' to cross each other in the upper region of the boiler, one tube of each adjacent pair in each longitudinal row is bent over into the vertical plane of its companion tube substantially at the points where the vertical and inclined portions of the tubes merge. This structural feature is of great importance, because 30 permitting the use of practically twice as many upflow water tubes as would otherwise be possible with a given length of boiler housing in an arrangement where the tubes cross each other as shown, while still leaving ample passage space between the tubes for the gases of combustion.
 The intersecting rows of tubes 16 and 16' do not, in the preferred construction, extend quite the full length of the boiler; but 40 preferably terminate slightly short of the end walls of the boiler to permit the introduction of additional or auxiliary water heating tubes throughout the end areas of the fire box or combustion chamber. The 50 preferred arrangement at the rear end is illustrated in Figs. 5 and 6, wherein it will be seen that the rear end portions of the drums 9 and 12 and 9' and 12' are connected by groups of tubes 17 and 17', respectively.
 55 The tubes of each group are increasingly offset laterally toward the transverse center of the end wall of the boiler throughout their intermediate portions, each group occupying substantially half the end wall area. Throughout the greater part of their length 70 these tubes lie in two vertical planes, the tubes in one plane being staggered in relation to the tubes of the other plane, and a part of the space between the front and rear tubes being filled in with high temperature 75 cement 17^a or other suitable material extending between the rear side of each tube of the front row and the two adjacent tubes of the rear row lying therebehind; but to provide a narrower and more compact arcuate junction with the drums 9 and 9' than would otherwise be possible, the lower ends of certain of these tubes are offset laterally and inwardly where they enter the drums, as shown in Fig. 6. This structural detail, however, is optional; the important feature being the arrangement of upflow tubes 17, 17' in the end region of the boiler so disposed as to form a water tube end wall of the fire box or combustion chamber, completely covering and protecting the adjacent end wall 80 of the housing.
 60 Figs. 3 and 4 illustrate the water tube arrangement at the front of the boiler which forms a water tube front wall for the fire box or combustion chamber. The location and arrangement of the tubes 18 and 18' are similar to those of the tubes 17, 17'; but the tubes of the two groups are locally bent or offset throughout approximately a semi-oval slightly above their lower ends, as shown at 18^a and 18^b in Fig. 3, thereby forming between them a generally oval opening or space 19 which, as shown in Fig. 1, registers with the opening 20 in the front wall of the boiler housing, through which coal is supplied to the fire box. Sharp bends in these curved tubes are avoided in order to facilitate the passage of cleaners 90 through them.
 The structure as thus far described is complete for boilers where superheating of the steam is not required. The products of combustion rise between the inner baffles 13 and 13', flowing around the inner rows of water tubes 16 and 16' and the intersecting portions of all the rows 16 and 16' of water tubes; flowing thence over the upper edges of the baffles 13, 13' downwardly between the upper drums and the baffles, again flowing around the portions of the tubes 16 and 16' that lie outside the baffles 13, 13' thence around the lower edges of the baffles 14, 14', and upwardly between the baffles 14 and 14' and the side walls of the boiler housing, flowing around the water downflow tubes 15, 15', by which circulation the greatest possible amount of heat is absorbed by the water in the tubes. From the spaces 100 between the outer sides of the drums 12 and 12' the water is led off to the superheater, the 105 water tube front wall of the boiler being provided with a water tube front wall for the fire box or combustion chamber, completely covering and protecting the adjacent end wall of the housing.
 110 The structure as thus far described is complete for boilers where superheating of the steam is not required. The products of combustion rise between the inner baffles 13 and 13', flowing around the inner rows of water tubes 16 and 16' and the intersecting portions of all the rows 16 and 16' of water tubes; flowing thence over the upper edges of the baffles 13, 13' downwardly between the upper drums and the baffles, again flowing around the portions of the tubes 16 and 16' that lie outside the baffles 13, 13' thence around the lower edges of the baffles 14, 14', and upwardly between the baffles 14 and 14' and the side walls of the boiler housing, flowing around the water downflow tubes 15, 15', by which circulation the greatest possible amount of heat is absorbed by the water in the tubes. From the spaces 115 between the outer sides of the drums 12 and 12' the water is led off to the superheater, the 120 water tube front wall of the boiler being provided with a water tube front wall for the fire box or combustion chamber, completely covering and protecting the adjacent end wall of the housing.
 125 The structure as thus far described is complete for boilers where superheating of the steam is not required. The products of combustion rise between the inner baffles 13 and 13', flowing around the inner rows of water tubes 16 and 16' and the intersecting portions of all the rows 16 and 16' of water tubes; flowing thence over the upper edges of the baffles 13, 13' downwardly between the upper drums and the baffles, again flowing around the portions of the tubes 16 and 16' that lie outside the baffles 13, 13' thence around the lower edges of the baffles 14, 14', and upwardly between the baffles 14 and 14' and the side walls of the boiler housing, flowing around the water downflow tubes 15, 15', by which circulation the greatest possible amount of heat is absorbed by the water in the tubes. From the spaces 130 between the outer sides of the drums 12 and 12' the water is led off to the superheater, the water tube front wall of the boiler being provided with a water tube front wall for the fire box or combustion chamber, completely covering and protecting the adjacent end wall of the housing.

and 12' and the opposite walls of the boiler housing the products of combustion pass to any suitable point of discharge, such as a chimney or smokestack (not shown). As to the flow of the water, the feed water may be injected either into the upper drums 12, 12', or into the lower drums 9, 9', which latter are constantly maintained full of water. From these latter the water flows upwardly through the tubes 16, 16' into the drums 12' and 12, respectively, giving off the steam generated during such flow. The water in the drums 12, 12' that is not evaporated into steam flows downwardly through the tubes 15, 15', back into the water drums 9, 9', and thence upwardly through the tubes 16, 16'. This takes place throughout the major portion of the boiler, but at the end portions the upflow of water from the drum 9 is direct to the drum 12 through the tubes 17 and 18, and from the drum 9' to the drum 12' through the tubes 17' and 18'. It will thus be seen that the fire chamber is formed with water tube walls on its sides, ends and top, so that a very large heating surface is provided and the heated products of combustion circulating through and flowing from the fire chamber are most efficiently used to promote the rapid flow of the water through the tubes and a correspondingly rapid generation of steam. The path of the products of combustion is mostly counter-flow to that of the water, which effects a desirable method of heat exchange. The arching of the tubes in intersecting fashion throughout the top area of the fire chamber also enables the radiant heat of the fuel to be most directly and efficiently applied to the generation of steam. The lower portions of the two lower drums 9, 9' serve as settling chambers for mud and scale which can be easily blown from the bottom of each drum by means of blow-off cocks, or washed out through washout plug holes made accessible by application of manholes located in one or both ends of each lower drum, said manholes being indicated at 9^a. The two upper drums provide a large steam liberating surface when the working water level is maintained near the center line of the drums. A large steam space is also provided in the upper portion of the top drums over the water. The upper drums are also provided with manholes indicated at 12^a to permit access for cleaning the tubes.

The described construction adapts itself well to the application and use of a steam superheater where desired, and in the drawings I have illustrated the application of such a superheater. 21 and 21' designate a pair of cylindrical steam headers located alongside the inner upper portions of the upper steam drums 12 and 12', respectively. 22 designates each of a longitudinal row of

steam pipes fitted into the upper portion of the drum 12 and continuous with horizontal coils 23 that are located in the top portion of the boiler housing directly over the upper ends of the inner baffles 13, 13'. The lower legs of these coils connect by pipes 24 into the steam header 21'. A similar row of pipes 22' connected into the upper portion of the drum 12' connect with similar superheater coils 23' that are internested with the coils 23, the lower limbs of said coils 23' communicating by pipes 24' with the superheater steam header 21. It is manifest that by reason of the location of the superheater coils 23, 23' they are subject to the heating influence of the products of combustion at nearly the hottest stage of the latter. Of course, the superheater pipes may return to the same side of the boiler from which they start.

Within the drums 12 and 12' I have shown longitudinally extending baffles 25, 25' underlying the receiving ends of the pipes 22, 22' to deflect particles of water and prevent the latter from passing over with the steam into the superheaters.

Where it may be desired to equip the boiler with a mechanical stoker, this may be readily accomplished; and in Figs. 1 and 3 I have shown a pair of stoker tubes 26 entered through the front wall of the boiler housing above and on opposite sides of the fire door opening; the tubes 18 and 18' being locally spread apart at points behind the openings for the stoker tubes, as shown at 18^a and 18^b in Fig. 3 to permit the passage of the stoker tubes between them.

It is believed that the principle of the invention, its novel structural features, and the numerous advantages inherent therein will be readily understood by engineers and others familiar with the art of boiler construction without further detail description. Manifestly, the number, spacing and grouping of the tubes will be more or less varied to suit the sizes and capacities of different boilers, and the details of structure and arrangement may be otherwise considerably modified from those herein shown without involving any departure from the principle of the invention or sacrificing any of the advantages and utilities thereof. Hence, I reserve all such variations and modifications as come within the spirit and purview of the appended claims.

I claim—

1. In a boiler of the type described, the combination of a housing of generally rectangular form, drums disposed in and lengthwise of the corner regions of said housing, and one or more longitudinal rows of water tubes connecting each lower drum with the upper drum on the opposite side and unitedly forming the roof of the fire box, the tubes of adjacent pairs in each row

being bent into a common vertical plane throughout the roof region to provide increased space for the intersection of said tubes.

- 5 2. In a water tube boiler, the combination of a generally rectangular housing, drums disposed in and lengthwise of the corner regions of said housing, two groups of water tubes connecting the lower and upper drums 10 on each side of the boiler, respectively, just inwardly of an end wall of the latter, the tubes of each group being bent inwardly throughout their intermediate portions to cover substantially one-half of said end 15 wall, and said tubes throughout their intermediate portions being disposed in front and rear closely adjacent vertical transverse rows, with the tubes in one row in staggered relation to the tubes in the other row, and a 20 filling of fire-resisting material between the rear side of each tube of the front row and the two adjacent tubes of the rear row lying therebehind.
3. In a boiler of the type described, the 25 combination of a housing of generally rectangular form, drums disposed in and lengthwise of the corner regions of said housing, and one or more longitudinal rows of water tubes connecting the inner side of 30 each lower drum with the inner side of the upper drum on the opposite side of the boiler, said tubes extending vertically for some distance from the lower drums and thence obliquely to their connections with the upper 35 drums, and the oblique portions of alternate tubes in each row being bent into the vertical plane of adjacent tubes whereby the space vacated by the bent tubes on one side

40 accommodates the tubes extending from the opposite side, thereby leaving between the intersecting tubes a sufficient space for passage of the gases of combustion.

4. In a water tube boiler, the combination of a generally rectangular housing, drums located in and lengthwise of the corner regions of said housing, water upflow tubes connecting the lower drum on each side with the upper drum on the opposite side, water downflow tubes connecting the upper and lower drums on each side, baffle plates 45 extending from said lower drums upwardly through said water upflow tubes to points above the latter and between said upper drums, and steam superheater coils disposed crosswise of the upper ends of said baffle plates and connected into said upper drums. 50

5. In a water tube boiler, the combination of a generally rectangular housing, drums located in and lengthwise of the corner regions of said housing, water upflow tubes 60 connecting the lower drum on each side with the upper drum on the opposite side, water downflow tubes connecting the upper and lower drums on each side, baffle plates 65 extending from said lower drums upwardly and inwardly through said water upflow tubes to points above the latter and between said upper drums, steam headers located opposite the inner sides of said upper drums, and steam superheater coils disposed crosswise of the upper ends of said baffle plates, 70 each of said superheater coils being connected at one end into one of said upper drums and at its other end into one of said steam headers.

LOREN P. MICHAEL.
